UNITED STATES PATENT OFFICE.

LEOPOLD KABIS, OF CHEYENNE, WYOMING, ADMINISTRATOR OF THOMAS MOORE, DECEASED.

DESIGN FOR A BUCKLE.

SPECIFICATION forming part of Design No. 29,281, dated August 30, 1898.

Application filed July 27, 1898. Serial No. 687,046. Term of patent 14 years.

To all whom it may concern:

Be it known that THOMAS MOORE, deceased, late a citizen of the United States, and a resident of Cheyenne, county of Laramie, and 5 State of Wyoming, duly invented and produced a new and original Design for Buckles, of which the following is a full, clear, and exact description, reference being had to the accompanying drawing, forming a part hereof.

10 The figure is a plan view of a buckle embodying the new design.

As shown in the drawing, the leading or material feature of the design consists of a large elongated oval frame 1, a portion 2 of the upper horizontal side of which is enlarged 15 in diameter, and immediately below said enlarged horizontal portion is the smaller elongated oval 3, the lower horizontal side 4 of

which is enlarged, and extending from the ends of said lower horizontal side to the ends 20 of the lower horizontal side of the loop 1 are the bars 5. At the center of the lower horizontal portion of the loop 1 are the flanges 6, and extending from a point between said flanges to the center of the lower portion 4 of 25 the loop 3 is a small bar 7.

What is claimed is—

The design for a buckle, substantially as herein shown and described.

In testimony whereof I affix my signature 30 in presence of two witnesses.

LEOPOLD KABIS,

Administrator of Thomas Moore, deceased.

Witnesses:

WALTER R. STOLL,
W.M. R. SCHNITGER.
